(57) **CLAIM**

The ornamental design for a fuel transfer pump as shown and described.

DESCRIPTION

FIG. 1 is a front perspective view of a fuel transfer pump, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof; and,

FIG. 7 is a bottom plan view thereof.

The dashed broken lines in the figures are for the purposes of illustrating portions of the fuel transfer pump, which form no part of the claimed design.
